UNITED STATES PATENT OFFICE

2,187,613

CONTROLLER

John T. Nichols, Pittsburgh, Pa., assignor, by
mesne assignments, to The Brown Instrument
Company, Philadelphia, Pa., a corporation of
Pennsylvania

Application July 17, 1933, Serial No. 680,886
Renewed June 17, 1939

9 Claims. (Cl. 250—41.5)

This invention is a controller adapted for use wherever conditions are such that a variable light is produced. For instance, it may be used to control any furnace which operates at sufficiently high temperatures to produce light, or wherever the operation of a photometric pyrometer is possible.

Fundamentally, the invention embodies the combination of a furnace having a heat control, a photoelectric unit arranged to receive light from the interior of this furnace, another photoelectric unit, some means for illuminating this other unit and a means controlled by the relative conductivities of these two units for operating the furnace's heat control. The illuminating means mentioned may be variable, whereby furnace temperature variations are provided. Also, this illuminating means may be provided with a means which varies it proportionately to the operation of the heat control, for the purpose of preventing drifting.

More specifically, the two photoelectric units are arranged to produce an electrically balanced circuit, and the illuminating means may be an electric lamp energized by a constant current source. This lamp may have a diaphragm between it and the secondly mentioned unit, which provides an opening of adjustable proportions so that the light received by this unit may be varied, and, in addition, a small resistance may be placed in series with this lamp and controlled by the operation of the furnace's heat control. The means for operating this heat control may then be controlled by the balanced or unbalanced condition of the circuit as produced by the two photoelectric units.

The accompanying diagram illustrates a specific example of the invention. The two photoelectric units 1 and 2 are connected in series by a line 3 and to batteries 4 and 5, also connected in series, by lines 6. The unit 1 is enclosed by a casing 7 and receives its light through a lens 8 and screen 9, it being understood that this light is that which is to be measured or, in other words, the light which comes from the interior of a furnace A. The unit 2 is provided with an illuminating lamp 10 whose light must pass through a screen 11 and an iris diaphragm 12, the latter being controlled by a ring 13 through the usual mechanism. These elements are shielded against extraneous light by a casing 14. This lamp is, in effect, a variable illuminating means.

A three-element vacuum tube 15 has its anode connected to the positive side of the battery 4

through a battery 16 in series therewith. The tube's grid is connected to the line 3 between the two units by a line 17, and its cathode is connected between the batteries 4 and 5 by a line 18.

A galvanometer relay 19 is connected in series with the line 18 so that it is operated by the output of the tube 15. This galvanometer relay includes a movable contactor 20 and two fixed contacts 21 and 22, and has a weighted movement which causes it to operate at a current value corresponding to the sensitive portion of the tube's characteristics. Thus this relay is balanced so that its contact 20 is free from its fixed contacts 21 and 22 when the two units 1 and 2 have equal conductivities. In other words, this relay 19 is a switching means controlled by the current between the units 1 and 2 and the current sources 4 and 5, or is a switching means controlled by the relative conductivities of these two units.

A battery 23 is connected to the lamp 10 by lines 24 through a small variable resistance 25. Assuming the resistance 25 to be set so that the lamp 10 produces a light having a constant value and that the diaphragm 12 is set to pass a certain amount of this light, it is apparent that the relay 19 will operate whenever the conductivity of the unit 1 varies from that of the unit 2. Therefore, by adjusting these variables so that the unit 2 is illuminated the same as the unit 1 when the furnace A is at a determined temperature, the galvanometer relay 19 operates whenever the temperature of the furnace A varies from this determined value. Obviously, the contacts 20, 21 and 22 may be used to control the furnace's temperature by the use of suitable apparatus.

In the present instance, the furnace A is heated by a resistance 26 which is powered by lines 27 through a variable resistance 28, the latter constituting the furnace's heat control. The movable contactor 20 of the resistance 28 is operated by a reversing motor 29 through a shaft 30, this motor also driving a second shaft 30a which moves the movable contactor 25a of the resistance 25, the latter being that controlling the current to the lamp 10.

The motor 29 is connected to the lines 27 by lines 31 and is controlled by the contacts of the galvanometer relay 19 through a relay 32. Thus, the motor 29 will operate in one direction or another, under the control of the galvanometer relay 19 which is, in turn, controlled by the current between the units 1 and 2. The furnace control is not more particularly described be-

cause of its many variations. For instance, the furnace A may be fired by gaseous fluid, in which case the motor 29 may control damper or valve systems.

5 In operation, the diaphragm 12 is adjusted by its ring 13 to pass a proper quantity of light, this ring being preferably provided with marks suitably calibrated in temperature readings. Other forms of light valves may be used. When the 10 furnace A is at the thusly determined temperature, the units 1 and 2 will have equal conductivities and the contact 20 will be free from its fixed contacts. The screens 9 and 11 may be colored to pass monochromatic red light so as to render any "black body" corrections of little consequence. Also, the screens may be shaded differently to correct the units 1 and 2, should the latter have 15 different characteristics.

If the temperature in the furnace A should 20 decrease, the conductivity of the unit 1 becomes less than that of the unit 2, the grid of the tube 15 becomes negative and the current through the relay 18 decreases. This causes the contact 20 to close with one or another of its fixed contacts 25 and effect operation of the motor 29 in a direction which removes some of the resistance 28.

Simultaneously, some of the resistance 25 is removed from the lamp 10 so that the illumination of the unit 2 is slightly increased, this preventing 30 drifting of the system as a whole. If the temperature of the furnace becomes higher so that the unit 1 is illuminated more brightly than the unit 2, the reverse of the foregoing occurs. It is assumed throughout that the contacts 20, 21 and 35 22, the relay 32 and the control leads of the motor 29 are suitably associated to produce the operations described. The association may be effected by any electrician.

The effect of the adjustment of resistor 25 is 40 such as to raise the control point, or normal temperature which the system tends to maintain, in response to a decrease in furnace temperature and to lower the control point on an increase in that temperature with the net result that the 45 tendency will be for a charge being heated in said furnace to be maintained at a constant temperature notwithstanding changes in furnace load.

Although a specific form of this invention has 50 been shown and described in accordance with the patent statutes, it is not intended to limit the scope of the invention exactly thereto, except as defined by the following claims.

I claim:

1. The combination of a furnace having a heat 55 control, a photoelectric unit arranged to receive control, a photoelectric unit arranged to receive light from the interior of said furnace, a second light from the interior of said furnace, a second photoelectric unit, variable illuminating means for said second unit, means controlled by the relative conductivities of said units for operating 60 said heat control and means for varying said illuminating means proportionately to the operation of said heat control.

2. The combination of a furnace having a heat 65 control, a photoelectric unit arranged to receive light from the interior of said furnace, a second photoelectric unit, means for illuminating said second unit so that its conductivity is the same as the first named unit when said furnace is at a determined temperature, means controlled by the 70 relative conductivities of said units for operating said heat control and means for slightly varying the illumination of said second unit proportionately to the operation of said heat control.

3. The combination of a furnace having a heat 75 control, at least two photoelectric units connected

in series, one of said units being arranged to receive light from the interior of said furnace and the other being provided with a variable illuminating means, a plurality of current sources connected in series to energize said units, switching means controlled by the current between said units and their current sources, means controlled by said switching means for operating said heat control, means for manually varying said illuminating means and automatic means for slightly varying said illuminating means proportionately to the operation of said heat control. 5

4. The combination of a furnace having a heat control, at least two photoelectric units connected 15 in series, one of said units being arranged to receive light from the interior of said furnace and the other being provided with an illuminating lamp, a plurality of current sources arranged in series to energize said units, a grid controlled electronic tube having its grid controlled by the 20 current between said units and their current sources, a relay switching system controlled by the output of said tube, and a reversing motor controlled by said system and operatively connected to said heat control. 25

5. The combination of a furnace having a heat control, at least two photoelectric units connected 30 in series, one of said units being arranged to receive light from the interior of said furnace and the other being provided with an illuminating lamp, a plurality of current sources arranged in series to energize said units, a grid controlled electronic tube having its grid controlled by the 35 current between said units and their current sources, a relay switching system controlled by the output of said tube, and a reversing motor controlled by said system and operatively connected to said heat control, said lamp having a current source connected thereto and a variable resistance in series therewith, the latter being 40 operatively connected to said motor. 45

6. The combination of a furnace having a heat control, at least two photoelectric units connected 50 in series, one of said units being arranged to receive light from the interior of said furnace and the other being provided with an illuminating lamp, a plurality of current sources arranged in series to energize said units, a grid controlled electronic tube having its grid controlled by the 55 current between said units and their current sources, a relay switching system controlled by the output of said tube, and a reversing motor controlled by said system and operatively connected to said heat control, said lamp having a manually adjustable light valve between it and the 60 second named unit. 65

7. The combination of a furnace having a heat control, at least two photoelectric units connected 65 in series, one of said units being arranged to receive light from the interior of said furnace and the other being provided with an illuminating lamp, a plurality of current sources arranged in series to energize said units, a grid controlled electronic tube having its grid controlled by the 70 current between said units and their current sources, a relay switching system controlled by the output of said tube, and a reversing motor controlled by said system and operatively connected to said heat control, said lamp having a current source connected thereto and a variable resistance in series therewith, the latter being 75 operatively connected to said motor, said lamp also having a manually adjustable light valve between it and the second named unit. 80

8. The combination of a furnace having a heat 85

control, a photoelectric unit arranged to receive light from the interior of said furnace, a second photoelectric unit, variable illuminating means for said second unit, automatic means controlled by the relative conductivities of said units for operating said heat control and automatic means for varying said illuminating means proportionately to the operation of said heat control.

9. The combination of a furnace having a heat control, at least two photoelectric units connected in series, one of said units being arranged to receive light from the interior of said furnace and

the other being provided with an illuminating means, a plurality of current sources connected in series to energize said units, a grid controlled electronic tube having its grid controlled by the current between said units and their current sources, a galvanometer relay connected for operation by the output of said tube and constructed to operate at a current value corresponding to the sensitive portion of said tube's characteristics, and means controlled by said relay for operating said heat control.

JOHN T. NICHOLS.
